INVENTOR

WILLIAM KORB

By James N. Ramsey
ATTORNEY

UNITED STATES PATENT OFFICE.

WILLIAM KORB, OF CHEVIOT, OHIO.

METHOD OF MANUFACTURING AUTOMOBILE RADIATORS.

Application filed May 30, 1924. Serial No. 716,840.

To all whom it may concern:

Be it known that I, WILLIAM KORB, a citizen of the United States, residing at Cheviot, in the county of Hamilton and 5 State of Ohio, have invented certain new and useful Methods of Manufacturing Automobile Radiators, of which the following is a specification.

My invention relates to radiator cores 10 particularly adapted for use in cooling water adapted to lower the temperature of internal combustion engines.

Heretofore it has been the practice among manufacturers of automobile radiator cores 15 to form two sheets of metal, one different from the other; the one being adapted to be inserted between the other sheet, after being cut and seamed together, whereby a section is formed for the purpose of comprising a 20 plurality of tubes adapted when combined with other sections to provide admittance of water between said sections and over said tubes.

The objects of my invention are to provide 25 means adapted to simplify the construction of radiator cores; to provide means adapted to affect a great saving in material; to provide means for constructing a radiator core from a plurality of pieces of sheet metal 30 each being formed similar to the other, whereby the use of but one form of die is required, thereby greatly reducing the cost of manufacturing said core; to provide a simple, efficient, economical and practical radiator core having adaptability to be constructed from a plurality of similar pieces 35 of formed sheet metal and which operations being successively performed considerably reduce the usual time required in manufacturing a radiator core; and to provide a radiator core having adaptability to perform efficient service and having similar appearance to radiators heretofore manufactured.

My invention consists in forming a plurality of pieces of sheet material similar to one another, so that when each piece is bent upon itself a plurality of times, a section is formed which when combined with a plurality of other similar sections, a radiator 50 core is formed having a space between adjacent sections adapted to permit the flow of water therethrough and over the walls of the sections each having an air space therebetween, whereby the temperature of said 55 water is adapted to be lowered.

My invention further consists in the de-

tails of construction, combination, arrangement and location of parts, as herein set forth and claimed.

In the drawing:

Fig. 1 is a perspective view of my radiator core showing a portion thereof broken away;

Fig. 2 is a vertical section showing two sections of my radiator core, and broken away;

Fig. 3 is a perspective view of my formed metal sheet; and

Fig. 4 is a front elevation of the same after successive operations are performed.

In the preferred construction of my invention I provide metal sheet 1 stamped, 70 pressed and formed by suitable means to a form shown in Fig. 3 with the longitudinal edges 2 and 3 or 2' and 3' bent at right angles to body 4. Longitudinal edge 3' may be extended to the position shown in Fig. 3 75 when it is desired to provide a full size button at the top and bottom of the radiator core, as will be hereinafter explained. Integral with the sheet and intermediate edges 80 2 and 3 are a plurality of equi-distance spaced apart and transversely and longitudinally aligned tongues 5 extending outwardly in parallel relation to edges 2 and 3. The tongues are formed from a portion of the sheet thereby providing perforations 6 85 adjacent each tongue. The tongues are arranged in groups 7 and 8, respectively, having notches 9 and 10 formed in body 4 adjacent the respective outer tongues 11 and 12 of the two groups. Group 7 is adjacent 90 transverse edge 13 of body 4 and separated therefrom by angular strip 14 having 60° angular portion 15 adjacent each perforation between the tongues. Angular portions 15 have apexes 16, respectively, adjacent the transverse center portion of perforations 6 and apexes 17, respectively, adjacent outer edges 18 of the tongues. Group 8 of tongues 5 is intermediate and extends parallel to transverse edges 13 and 19 of body 100 4 and extends parallel also to group 7.

Angular strips 20 and 21, respectively, are adjacent group 8 of tongues 5 and disposed on either side thereof and extend parallel thereto. The angular strips 20 and 21 each comprise 60° angular portion 22 somewhat wider but of similar formation to angular portions 15 of strip 14. Angular portions 22, respectively, have apexes 23 and 24, respectively, in alignment with apexes 16 and 17 of strip 14.

Angular strip 25 adjacent transverse

edge 19 of body 4 also is composed of angular portions 22, respectively, in alinement with angular portions 22 of angular strips 20 and 21, respectively. Adjacent the inner edge 26 of group 7 of tongues 5 is angular strip 27 having angular portions 22, respectively, in alinement with angular portions 22 in strips 20, 21 and 25.

Intermediate angular strips 20 and 27 and 21 and 25, respectively, are transverse strips 28 and 29 having curved depressions 30.

The sheet 1, as shown in Fig. 3, may be formed by suitable means after which strip 14 is bent with apexes 17 of angular portion 15 in engagement with outer edges 31 of tongues 5 in group 7. The tongues 5 in group 7 are then bent with inner edges 26, respectively, in engagement with apexes 32 of angular strip 27. The angular strip 20 is then bent with apexes 24 respectively in engagement with edges 33 of tongues 5 in group 8. The tongues 5 in group 8 are then bent with edges 34, respectively, in engagement with apexes 24 of angular portions 21. The angular strip 25 is then bent with apexes 23 and 24, respectively, in engagement with apexes 16 and 17 of angular strip 14 and overlapping edges 2' and 3', respectively, are soldered, whereby a section 30 of my radiator core is formed and ready for assemblage with other sections for the purpose of forming a radiator core 36.

In Fig. 1 two sections 35 are shown in assembled position whereby water space 37 is formed at the top thereof thereby permitting the entrance of water therein. The water is adapted to drain downwardly over walls 38 of the adjacent sections, thereby being cooled by currents of air passing through air spaces 39. The outer ends 40 of the sections are secured together by suitable means, as by dipping in a bath of solder, thereby securing the sections together and sealing the ends of water spaces 37.

Longitudinal edge 3 may be extended to 3', as shown in Fig. 3, whereby a full size button or cell 41 is formed at the top and bottom, respectively, of each section 35.

An advantage of my invention is that for the purpose of manufacturing my radiator core I merely provide myself with a plurality of flat pieces of metal, all of which may be formed by the use of the same die and press, thereby eliminating the expense occasioned by the investment of various types of dies, as well as considerably affecting the advantageous features of my invention from the standpoint of reduced labor and material costs compared with the usual method of manufacturing radiator cores. Although I have devised means by which a radiator core may be quickly, efficiently and economically manufactured, I have also provided a construction which is adapted to perform the 65 functions intended with great efficiency and

with little likelihood of the core itself requiring repairs or other attention due to the vibrations and shocks which it may receive.

It is apparent that I have invented a simple, efficient, and practical radiator core 70 whereby it is not necessary to employ the use of various pieces of machinery for pressing the same and that it is not necessary to carry an overly large stock of material inasmuch as my complete core is manufactured 75 from similar pieces of flat sheet material.

While I have chosen to illustrate the form of construction of my invention by the herein drawings and explanation of the same, I desire to emphasize the fact that the form 80 and the explanation as relates thereto, are not intended to include the various forms of modification, in which my invention may be incorporated. It is understood that my invention resides in the combination, arrangement of parts and the details of construction, as hereinafter claimed, and that changes in the precise embodiment of the invention as herein disclosed can be made within the scope of what is claimed without departing from the spirit of the invention.

What I claim as new and desire to secure by Letters Patent is:

1. A method of manufacturing a section of a radiator core comprising first forming 95 a sheet of metal having a plurality of notches therein, a pair of grouped spaced apart alined perforations therein, a plurality of tongues integral with said sheet and one of said tongues extending outwardly therefrom 100 adjacent each of said perforations, said sheet also having corrugations extending longitudinally thereof, then bending one end of said sheet in engagement with the outer edges of one group of said tongues, then bending 105 said sheet in engagement with the inner edges of said last group of said tongues, then bending said sheet in engagement with the inner edges of the other group of said tongues, then bending said sheet in engagement 110 with the outer edges of said tongues in said last group.

2. A method of manufacturing a radiator core comprising first forming a sheet of metal having a plurality of notches therein 115 and having its longitudinal edges bent at right angles to said sheet and having a pair of grouped spaced apart alined perforations therein, and having a plurality of tongues integral therewith extending outwardly 120 therefrom adjacent each of said perforations, respectively, said sheet also having corrugations extending longitudinally thereof, then bending one end of said sheet in engagement with the outer edges of one 125 group of said tongues, then bending said sheet in engagement with the inner edges of said last group of said tongues, then bending said sheet in engagement with the inner edge of the other group of said 130

tongues, then bending said sheet in engagement with the outer edges of said tongues in said last group, whereby a section is formed and then securing the outer side of said section in engagement with the outer side of a similar section whereby a water space is formed between said sections.

3. A method of manufacturing a radiator core comprising first forming a sheet of metal having a plurality of notches therein and having its longitudinal edges bent at right angles to said sheet, and having a pair of grouped spaced apart alined perforations therein having a plurality of tongues integral with said sheet and extending outwardly therefrom and adjacent said perforations, respectively, said sheet also having corrugations extending longitudinally thereof and in alinement with said perforations, respectively, then bending one end of said sheet in engagement with the outer edges of one group of said tongues, then bending said sheet in engagement with the inner edges of said last group of said tongues, then bending the sheet in engagement with the inner edges of the other group of said tongues, then bending said sheet in engagement with the outer edges of said last groups of tongues, whereby a section is formed having their outer respective ends polygonally formed whereby air currents are adapted to be admitted therethrough for the purpose of cooling the walls, then securing the outer sides of said section in engagement with the outer side of other similar sections, substantially as described.

4. A method of manufacturing a radiator core comprising forming a sheet of metal so that a plurality of notches are formed therein and having its longitudinal edges bent and having a pair of grouped spaced apart perforations therein, and two groups of tongues integral with said sheet and ex-

tending outwardly therefrom and having corrugations extending longitudinally thereof, then bending one end of said sheet in engagement with the outer edges of one group of said tongues, then bending said sheet in engagement with the inner edges of said last group of said tongues, then bending the sheet in engagement with the inner edges of the other group of said tongues, then bending said sheet in engagement with the outer edges of said last group of tongues whereby a section is formed, then securing the outer sides of said section in engagement with the outer sides of other similar sections whereby water spaces are formed between said sections, substantially as described.

5. A method of manufacturing a radiator core comprising first forming a sheet of metal having a plurality of notches therein and having its longitudinal edges bent at right angles to said sheet and having a pair of grouped spaced apart alined perforations therein, a tongue integral with said sheet and extending outwardly therefrom adjacent each of said perforations, said sheet also having corrugations extending longitudinally thereof and in alinement with said perforations respectively, then bending one end of said sheet in engagement with the outer edges of one group of said tongues, then bending said sheet in engagement with the inner edges of said last group of said tongues, then bending the sheet in engagement with the inner edges of the other group of said tongues, then bending said sheet in engagement with the outer edges of said tongues in said last group, whereby a section is formed, then securing the outer side of said section in engagement with other similar sections whereby a water space is formed between said sections.

WILLIAM KORB.
